UNITED STATES PATENT OFFICE.

FREDERICK MILLER AND HUGHLETT L. NOE, OF WAMEGO, KANSAS.

GAME APPARATUS.

Application filed September 12, 1922. Serial No. 587,758.

To all whom it may concern:

Be it known that FREDERICK MILLER and HUGHLETT L. NOE, citizens of the United States, residing at Wamego, in the county of Pottawatomie and State of Kansas, have invented certain new and useful Improvements in Game Apparatus, of which the following is a specification.

The present invention relates to a chance device, which may be used alone, or in connection with other game apparatus.

An important object of the invention is to provide a chance device of the above mentioned character, which is adapted to be rolled forwardly upon a surface and will automatically return, and when coming to rest will indicate certain data, which may be employed, if desired, in playing games.

A further object of the invention is to provide a rolling cylinder, having characters arranged thereon, and a weighted pointer located in cooperative relation to the characters, with means to cause a return movement of the cylinder, such means being constructed to permit of the cylinder stopping with the pointer adjacent to any selected surface of the cylinder or character thereon.

A further object of the invention is to provide means to lock the weight to the revolving cylinder, so that all parts will then rotate as a unit, upon the end of the forward movement, such means automatically releasing the connection between the weight and cylinder when the weight returns to the normal position.

A further object of the invention is to provide a device of the above mentioned character, which is simple in construction, strong and durable.

Other objects and advantages of the invention will be apparent during the course of the following description.

In the accompanying drawings forming a part of this specification and in which like numerals are employed to designate like parts throughout the same,

Fig. 1 is a side elevation of a device embodying our invention,

Fig. 2 is a central vertical longitudinal section through the same,

Fig. 3 is an end elevation of the device,

Fig. 4 is a transverse section taken on line 4—4 of Fig. 2, and,

Fig. 5 is a similar view taken on line 5—5 of Fig. 2.

In the drawings, wherein for the purpose

of illustration is shown a preferred embodiment of our invention, the numeral 10 designates the body portion of the device, which is preferably in the form of a cylinder. This cylinder has wheels or rolling elements 11 rigidly secured in its opposite ends, by any suitable means. The wheels 11 project radially beyond the periphery of the cylinder 10 for a substantial distance, as shown. 65

The cylinder 10 is provided upon its periphery and near one end with an annular set of characters 12, which for the purpose of illustration are shown as numerals, arranged consecutively. The invention is in no sense 70 restricted to the use of any particular kind of characters, as the same may widely vary, as found advantageous.

The wheels 11 are provided centrally thereof with sleeves or bearings 13, rotatably receiving a shaft 14, provided at one end with a head 15.

Pivotedly mounted upon the shaft 14, between the head 15 and the adjacent wheel 11, is a pointer 16, maintained substantially 80 vertical by a weight 17 formed upon its lower end. The pointer is bent horizontally at its top, into a finger 18, provided with a pointer 19, arranged to travel in proximity to the characters 12. 85

The longitudinal displacement of the shaft 14 is prevented by washers 20 and 21. A transverse pin 22 is carried by the shaft 14, upon one side of the washer 20, as 90 shown.

In order that the shaft 14 may not ordinarily rotate to any considerable extent we provide a weight 23, preferably segmental, and having an opening 24 near its top, to receive the shaft 14, clamped therein by a set screw 25. 95

The numeral 26 designates a pair of curved leaf springs which are faced in opposite directions within the cylinder 10 and have corresponding ends secured thereto, as shown at 27, while the free ends of these leaf springs are adapted to be moved toward and away from the cylinder. Flexible elements 28, such as cords or the like, are suitably connected with the free ends of the leaf springs, and are connected with the shaft 14 and are oppositely wound thereon. 100

Means are provided to lock the weight 23 to the cylinder 10, so that all parts rotate as a unit, when the weight assumes an upper position, as indicated in Figure 4. Such means are in the form of rods 29, hinged 105

to the top of the weight, as shown at 30, and having their free ends adapted to drop into engagement with the periphery of the cylinder.

5 In operation, the device is held in the hand of the operator and rolled forwardly from him. This rolling movement causes the cords 28 to wind upon the shaft 14, and when the springs 26 are placed under sufficient tension, with regard to the momentum of the device, such springs will cause the device to roll rearwardly in its return movement. The cords will then be wound upon the shaft 14 in an opposite direction and 15 the device will stop and roll forwardly, and will come to rest. Particular attention is called to the fact that there is sufficient slack in the cords 28 whereby the cylinder may make a complete revolution without placing 20 the springs under tension, and this will permit the device coming to rest with the pointer 19 adjacent to any one of the several characters 12. This will give the device a large range, with respect to the element 25 of chance. When the device is rolled forwardly upon the winding impulse, with sufficient force whereby the springs 26 will draw the weight 23 to the upper position, Figure 4, then the rods 29 will drop into 30 engagement with the periphery of the cylinder 10, causing the entire mechanism to become a unit, in a further forward rolling. This will prevent the strings from unwinding from the shaft when the device is stationary, at the end of the winding movement.

40 The device is susceptible to various uses in connection with game apparatus, or may be used alone. The device is attractive and interesting in operation, and embodies a large range with respect to the element of chance.

45 It is to be understood that the form of our invention herewith shown and described is to be taken as a preferred example of the same, and that various changes in the shape, size, and arrangement of parts, may be resorted to without departing from the spirit of the invention or the scope of the subjoined claims.

50 Having thus described our invention, we claim:

1. In a device of the character described, a member adapted to be rolled and provided 55 with a group of characters extending about its axis of rotation, a shaft pivotally mounted upon the member, a weight mounted upon the shaft, means including a reacting yielding element permanently connecting the member and shaft, and a pointer pivotally mounted upon the shaft and having its lower end weighted and its opposite end arranged in cooperative relation to the group of characters.

65 2. In a device of the character described,

a rolling member provided upon its periphery with characters, a shaft pivotally mounted upon the member, a weight carried by the shaft to oppose its rotation, an elastic element connected with the member, a flexible 70 element permanently connecting the elastic element and shaft, and a pointer permanently pivotally mounted upon the shaft and having one end weighted and its opposite end traveling in proximity to the group 75 of characters.

3. In a device of the character described, a hollow rolling member provided with a group of characters extending about the axis of rotation thereof, means mounted within 80 the hollow rolling member to automatically return the rolling member at the end of its impulse travel, and an indicator arranged exteriorly of the rolling member and permanently pivotally connected with one end 85 of the member and having its lower end weighted, such lower weighted end being arranged exteriorly of the rolling member whereby the indicator remains substantially vertical when the member is traveling upon 90 its return movement, said indicator cooperating with the group of characters.

4. In a device of the character described, a rolling cylinder, a shaft pivotally mounted therein, a weight connected with the 95 shaft and projecting therebelow, a leaf spring secured to the cylinder and extending transversely thereof with its free end moveable approximately radially of the cylinder, a flexible element connecting the shaft and 100 the free end of the leaf spring, and a pointer permanently pivotally mounted upon one end of the shaft and weighted so that it remains in a substantially vertical position during the impulse and return travels of 105 the cylinder.

5. In a device of the character described, a rolling cylinder, a shaft pivotally mounted therein, said cylinder having a group 110 of characters surrounding said shaft, a weight secured to the shaft, a spring secured to the cylinder, a flexible element connecting the spring and shaft and adapted to be wound upon said shaft, said flexible element having sufficient slack whereby the cylinder may 115 rotate for substantially a complete revolution without winding the flexible element upon the shaft, and a pointer pivotally connected with the shaft and having one end cooperating with said characters and its 120 opposite end weighted.

6. In a device of the character described, a rolling member, a weight pivotally mounted thereon, a spring connected with the member, a flexible element connecting the spring 125 and weight, and separate means to automatically connect the weight and member when the weight is shifted to the upper portion of said member.

7. In a device of the character described, 130

a rolling member, a weight pivotally mounted thereon, resilient means connected between the weight and member, and automatic means to lock the weight to the member when the weight is shifted into the upper portion of said member.

8. In a device of the character described, a casing having a rolling portion, a weight pivoted upon the casing, resilient means connecting the weight and casing, and a rod pivotally connected with the weight and adapted to drop into engagement with the casing when the weight moves to the upper position in the casing.

9. In a device of the character described, a casing having a rolling portion, a shaft pivoted within the casing, a weight depending from the shaft, resilient means connected between the shaft and casing, and pivoted rods connected with the upper end of the weight.

10. In a device of the character described, a rolling cylinder, a shaft pivotally mounted therein, a weight secured to the shaft, a pair of leaf springs arranged within the cylinder and extending transversely thereof and having corresponding ends attached to the cylinder, the free ends of the leaf springs being movable approximately ra-

dially with respect to the cylinder, and 30 flexible elements connected with the free ends of the leaf springs and oppositely wound upon said shaft.

11. In a device of the character described, a rolling cylinder having a group of characters surrounding its axis of rotation, a shaft pivotally mounted within the cylinder, a weight secured to the shaft, a plurality of leaf springs extending transversely within the cylinder with corresponding ends thereof attached to the cylinder and their free ends being adapted to move approximately radially within the cylinder, flexible elements connected with the springs and oppositely wound upon said shaft, each 45 flexible element having sufficient slack whereby the cylinder may turn a selected amount without winding the flexible element upon the shaft, and a pointer permanently pivotally connected with the shaft 50 and having one end thereof cooperating with said characters and its opposite end weighted.

In testimony whereof we affix our signatures.

FREDERICK MILLER.
HUGHLETT L. NOE.
